UNITED STATES PATENT OFFICE.

JAMES C. GARRETT, OF SAN FRANCISCO, CALIFORNIA.

PNEUMATIC CLUTCH.

No. 927,229.

Specification of Letters Patent.

Patented July 6, 1909.

Application filed August 25, 1904. Serial No. 222,190.

To all whom it may concern:

Be it known that I, JAMES C. GARRETT, a citizen of the United States, and resident of San Francisco, in the county of San Francisco and State of California, have invented certain new and useful Improvements in Pneumatic Clutches, of which the following is a specification.

This invention is for the same subject matter as my application, Serial No. 129,113, filed October 28, 1902 for pneumatic clutches.

My invention relates to clutches, and has for its object to provide a new and novel device for minimizing the impact transmitted when connecting a rotating member to a member at rest, and to automatically control and direct the connection of the driving and driven members, in such manner, that the contacting jaws on the face of each clutching member will fully overlap each other when they contact.

The novelty of my invention consists in the use of imprisoned air to cushion and retard the impact transmitted by a moving member to a member at rest when motion is applied to said member at rest.

A further object is to provide means for regulating the transposition of the cushioning and retarding medium from the pressed to vacuum sides of the air compartments in the imprisoning cylinder, and for returning the compressor to its set or operative position after the clutch members have been disconnected.

The device is adapted to be used on same or separate shafts and may be employed to supply all the requirements of an ordinary clutch.

It is intended to provide a clutch, simple in its construction and combining the advantages of the "positive" with the yielding qualities of the "friction" type of clutches.

Other objects and advantages of the invention will appear in the course of the subjoined description.

In the construction here shown the driving and driven members are connected automatically, but they may be connected by the direct application of the actuating lever to the axially movable sleeve.

In the accompanying drawings Figure 1 is a horizontal section of my device on line X X, on Fig. 2, with the arm C broken away on line Y Y, showing the shape and fastening of the bracket B. Fig. 2 is a vertical cross

section of the line X¹ through Fig. 1, looking from the right and the connecting rods N removed. Fig. 3 is a front elevation of the disk and its inwardly extending arms shown in dotted lines and designated as "compressor." Fig. 4 is a vertical cross section on the line V V on Fig. 1 looking from the left. Fig. 5 is a portion of the external surface of the cylinder at the end connected to the driving member.

Similar letters designate corresponding parts in the various views of the drawing.

For convenience in describing my invention, I shall designate the circular device A keyed to the shaft O, the "cylinder" or "impelling member." The centrally projecting pieces secured to the concave surface of the cylinder and lettered B, shall be called the "brackets." The device operating inside of, and forming an inclosing end for the cylinder is called the "compressor" and lettered C. And the device pivoted to the sleeve E on the driven member and extending over the cylinder shall be designated as the "connecting rods" and lettered N and N'.

In the construction shown in Fig. 1 of the drawings, the cylinder A is made with one end open, the opposite end A¹ and the hub A² is constructed in one piece. The barrel of the cylinder is projected to a determined distance beyond the end A¹ as shown at A⁴, and provided with inclines A³ shown in Figs. 1 and 5 for a purpose which shall be hereinafter described. The cylinder A is secured to the driving member O, by the key O⁴ shown in Fig. 1, but the end of the cylinder and shaft may be made in one piece and provided with a flange adapted to be joined to a corresponding flange on the driving member. Grooves A⁶ are cut longitudinally in the concaved surface of the cylinder for the purpose of providing abutments for the projecting ribs B³, on the brackets B as shown in Fig. 2. These brackets are constructed with their plane or contacting surfaces B¹ in line with the diameter of the cylinder A to provide a suitable bearing for the contacting surfaces C² of the arms C¹ C² of the compressor and their convex surfaces neatly fitting to the concave surface of the cylinder A and provided with ribs B³ fitting neatly into the grooves A⁶ to brace against the impact exerted by the moving member O, when the clutch shoulders E² of the driven member are moved into connection with the clutch shoulders C³ on the disk of the compressor; the base B⁴ of these brackets

ets is held in position by countersunk rivets B⁶ passing through the base of the bracket B and the barrel of the cylinder A, as shown in Fig. 2.

5 The interposed connection C between the driving and driven members and designated as the compressor shown in Figs. 1, 2 and 3 consists of a construction composed of a disk, clutch shoulders and air compressing arms 10 extending from an enlarged center in opposite directions and having the shape shown in sectional view, Fig. 2.

Fig. 3 shows the face of the disk with the 15 location of the clutch shoulders C¹ on its surface and compressor arms C¹ in dotted lines, a projection of which is shown in Fig. 1. On the opposite side of this disk a circular groove C⁴ is cut, shown in dotted lines in Fig. 3 and in sectional view Fig. 1 of a dimension to 20 admit the insertion and operation of the edge A⁶ of the cylinder A. The arms C¹ C¹ are constructed to neatly fit and operate in the cylinder A. A hole C⁵ is bored horizontally from the center of the disk having a counter- 25 sunk enlargement C⁶ in the face of the disk, and extending inwardly between and through the arm C¹ C¹ and a threaded hole is sunk into the shaft O and a tap bolt O¹ is provided, having a flat head O² and its opposite end 30 suitably threaded.

Through each arm of the compressor C¹ C¹ a vertical hole C⁷ C⁷ shown in dotted lines in Fig. 2, is bored for the purpose of permitting the passage of air from one side of the arms 35 C¹ C¹ to the other, and from the face of the disk, Figs. 3, and 1, two holes C⁸ corresponding diameter are made horizontally so as to intersect the vertical holes C⁷ C⁷. These horizontal holes are provided with threads 40 and are countersunk for the purpose of permitting the head of the bolt C⁹ to sink beyond the surface of the disk. Bolts C⁹ C⁹ are provided for insertion in these holes having suitable threads on their shanks and their 45 head provided with grooves for the purpose of turning the bolts, by the operation of which the passage of air from one side of the arms C¹ C¹ to the other may be regulated or prevented as desired in the operation of the 50 clutch.

When the compressor is inserted into the cylinder, the edge A⁶ entering the groove C⁴ in the disk, the bolt O¹ is inserted into hole C⁵ in the compressor and screwed into its 55 position in the shaft O. The bolt head contacting with the counter-sunk seat C⁶ in the face of the disk, permitting the arms and end of the compressor to move freely but fit neatly to the inside surface and end of the 60 cylinder and the groove C⁴ on the rear side of the disk. Around the outside of the barrel of the cylinder and in proximity to the side of the disk of the compressor a coiled spring D is located, and a threaded pin D¹ is inserted into the shell of the cylinder barrel 65

against which one end of the spring is abutted; its other end is similarly abutted against the pin D¹ near the periphery of the disk. A depression D² is cut on the periphery of the disk of the compressor and a band or cover D³ having an inwardly turned right angle edge D⁴ adapted to fit closely to the surface of the cylinder and its other edge fitting to the depression D² on the disk, is provided and secured thereon as shown in Fig. 1 for the purpose of protecting the spring of the disk. By this provision it will be seen that when the driving and driven members are connected, the spring D will yield to the pressure of the driving member 70 and the air gradually exhausts from the pressed to the vacuum side of the arms C¹ C¹ until the arms C¹ rest on the plane contacting surface B¹ of the bracket; and when the clutch members are disconnected the spring 75 D will force the compressor back to its set or operative position prepared for the next connection.

In the construction shown in Fig. 1 of the drawings, the driven member O³ is provided with a sleeve E adapted to move axially thereon and revolute therewith. This sleeve is constructed with a disk E¹ having gripping members E² (shown in Fig. 1 and in dotted lines in Fig. 4) on its face, adapted to intermesh with corresponding members O³ on the disk of the compressor C, connected to the driving member. Near the opposite end of the sleeve a spider F is mounted on the sleeve E and adapted to move longitudinally by means of the auxiliary lever H independently of the sleeve actuating lever K, but is pivoted thereto at H¹; this auxiliary lever H in this case is constructed to encircle the sleeve or spider E, and is provided with pins H² shown by dotted lines in Fig. 1. The pins enter the groove F² and will, when the auxiliary lever is operated, move the spider in or out of restraining contact with the connecting rods. On the end of the sleeve E a removable ring E³ having a threaded inside surface is provided, and adapted to be screwed into and from its position on the end of the sleeve after the spider has been placed in position. The actuating lever K is pivoted to any convenient support and constructed in the form shown in Fig. 1.

The connecting rods N and N¹ shown in sectional view Fig. 1 are located in a longitudinal groove E⁴ cut in the sleeve E and pivoted in the jaws E⁵ as shown in Fig. 1, having a bearing against the back of the disk E carrying the clutch shoulders E⁶ on the driven member. Said bearing being at right angles to the direction of the force operating to connect the driven to the driving member. One end of these connecting rods is extended over the cylinder to a position near its projected edge A⁴ and is constructed with in- 120 125 130

wardly turned right angle hooks N^2 , as shown in Fig. 1. Their opposite ends are cut away at the inner edge N^1 contiguous to the sleeve and a spring N^4 is secured to the inner edge 5 of said rods, the free end of the spring N^4 pressing against the bottom of the groove E^4 in the sleeve E . This spring will, by reason of the centrally located pivot E^5 cause the opposite end of the rod to press against the 10 outside surface of the cylinder E , when the restraining ring F^2 of the spider is moved out of contact therewith and be raised and retained out of contact with said cylinder when the spider F is moved to the opposite 15 position shown in Fig. 1.

The actuating lever K is pivoted to any convenient support at K^1 and is constructed in the form of a circular band surrounding sleeve E . Into the top and bottom of this 20 band two inwardly projecting pins K^2 K^3 shown in dotted lines are inserted at determined distances apart and of a length that will contact with and move the sleeve E axially, so that assuming the spider to be 25 moved out of contact with the ends of the connecting rods, on moving the actuating lever K the pin K^2 will contact with the ring E^3 on the end of the sleeve, moving it in the direction of the driving member. The right 30 angle end of the hook N^2 will be forced into the incisure or cut away portion A^6 in the projecting end A^4 of the cylinder by the pressure of the springs N^4 , and the inclines A^3 will draw the sleeve on the driven member 35 axially with its clutch members E^2 into operative connection with the clutch members C^3 of the compressor connected with the driving member O ; and when the inclines A^3 contact with the hooks N^2 it is obvious that sufficient 40 distance has been provided between the pins K^2 and K^3 to permit the automatic movement of the ring E^3 on the sleeve E without contacting with the pin K^3 on the actuating lever K . The connecting rods will 45 then occupy the position shown by the broken rod N^1 in Fig. 1 and maintain such position until the rods N and N^1 are acted upon by the spider F . By this construction it will be seen that by reason of the position 50 of the incline A^3 on the projecting edge of the barrel of the cylinder the connecting movement is timed, and moved into complete operative connection by the action of the incline A^3 on the hook N^2 thus causing the 55 members to rotate in unison and on the connection being effected the hooks N , on the connecting rods will occupy a position contacting with the extended portion A^4 of the end of the cylinder, and retain the clutch 60 members in operative connection until the auxiliary lever H is operated to move the ring of the spider into contact with the ends N of the connecting rods and raise them out of contact with the end of the cylinder when 65 the clutch members may be disconnected.

Having now, it is believed, fully described my invention, what I claim and desire to secure Letters Patent for, is:

1. In a pneumatic clutch, the combination of a rotating shaft, fixed and revoluble members mounted thereon and forming an imprisoning inclosure for the cushioning medium, a driven member, means acting to contact said fixed and revoluble members and thereby rotate the driven member, and means to permit the cushioning medium to pass alternately from one portion to the other of the said air imprisoning inclosure. 70

2. In a clutch the combination of a revoluble shaft, a cylinder or impelling member fast thereon, a bracket within said cylinder, a compressor adapted to be rotated within said cylinder, and provided with an arm adapted to contact with the bracket, said arm having an aperture therein to permit the cushioning medium within the cylinder to pass alternately from one side of the compressor to the other, a driven member, and means for connecting and disconnecting the driven member and the compressor. 80

3. In a clutch the combination of a revoluble shaft, a cylinder or impelling member fast thereon, two oppositely arranged brackets within said cylinder, a compressor adapted to be rotated within said cylinder and provided with arms adapted to contact with said brackets, each arm having an aperture therein to permit the air to pass alternately from one side to the other of the arms, a driven member, and means for connecting and disconnecting the driven member and the compressor. 90

4. A power-transmitting device comprising a plurality of rotatable sections collectively forming a contractible air chamber, and means carried by one section to limit the independent rotation of the other section to contract the chamber and form a cushion of compressed air therein. 105

5. A power-transmitting device comprising a plurality of rotatable sections collectively forming a contractible air chamber, and means carried by one section to limit the independent rotation of the other section said chamber having a restricted air vent or outlet to permit the gradual escape of air from said chamber. 110

6. A power-transmitting device comprising two rotatable sections collectively forming a contractible air-chamber, said sections having heads or abutments which compress the air in said chamber and meet to positively engage the sections. 120

7. A power-transmitting device comprising two rotatable sections collectively forming a contractible air-chamber, one section carrying means to limit independent rotary movement of the other, one of said sections having a power-receiving portion and the other a clutch member, and a complementary 125

clutch member movable into and out of engagement with the first-mentioned clutch member.

8. A power-transmitting device comprising two rotary sections collectively forming a contractile air-chamber, said sections having air-compressing heads or abutments forming opposed ends of the air-chamber, and means for yieldingly holding said sections in position to extend the air chamber.

9. A power-transmitting device comprising, first, a section having a hub, a rim concentric with the hub, a web projecting inwardly from the rim, and a head or abutment extending crosswise of the rim; secondly, another section having a hub, a web projecting outwardly therefrom, an annular flange projecting from one side of the web, a

head or abutment extending crosswise of the annular flange, and a clutch member projecting from the opposite side of the web, said rim, webs, annular flange, and abutments forming a segment's compressible air-chamber of which the abutments are the ends, a spring connecting the two sections and yieldingly holding them in position to extend the air-chamber; thirdly, a shaft on which the hubs of said sections are mounted; and fourthly, a clutch member mounted on the shaft and movable into and out of engagement with the first mentioned clutch member.
